UNITED STATES PATENT OFFICE.

JOHN ROGERS FLANNERY, OF PITTSBURGH, PENNSYLVANIA, ASSIGNOR TO FLANNERY BOLT COMPANY, OF PITTSBURGH, PENNSYLVANIA.

STAY-BOLT STRUCTURE.

1,276,745.

Specification of Letters Patent. Patented Aug. 27, 1918.

Application filed November 21, 1916. Serial No. 132,607.

To all whom it may concern:

Be it known that I, JOHN ROGERS FLANNERY, a citizen of the United States, and a resident of Pittsburgh, in the county of 5 Allegheny and State of Pennsylvania, have invented certain new and useful Improvements in Stay-Bolt Structures; and I do hereby declare the following to be a full, clear, and exact description of the invention, such as will enable others skilled in 10 the art to which it appertains to make and use the same.

This invention relates to an improved stay bolt structure,—the object of the invention 15 being to provide means in a stay bolt having a tell-tale hole or bore, whereby the condition of the bolt may be determined without removing the bolt.

With this and other objects in view, the 20 invention consists in certain novel features of construction, as hereinafter set forth and pointed out in the claims.

In the accompanying drawings; Figure 1 is a sectional view of a stay bolt structure 25 showing one embodiment of my invention; Figs. 2 and 3 are views of modifications.

1 represents an outer boiler sheet and 2 an inner boiler sheet. In the construction shown in the drawing, the outer boiler sheet 30 is made with a hole having a threaded wall for the reception of an externally threaded bearing sleeve 3,—the inner wall of the latter being formed with a curved bearing face 4 for the accommodation of the spherical head 35 5 of a stay bolt 6 and a portion of the bore of the bearing sleeve is made flaring as at 7 to permit lateral movement of the bolt. The head of the bolt is inclosed by means of a cap 8 which screws onto the sleeve 3 and 40 may be formed with a shoulder 9 to engage the end of said sleeve,—the interior configuration of said cap being such as to form a clearance space 10. The inner end of the bolt 6, in the structure shown in the drawing, may be threaded to pass through a suitable hole in the inner boiler sheet 2 and may 45 be upset as shown at 11.

The bolt is provided with a bore 12 which, in the embodiment of the invention shown 50 in the drawing may extend from one end of the bolt to a point in proximity to the head 5 thereof,—the outer end of said bore thus being closed. A material 13 which is sensitive to the action of water is inserted into 55 the bore 12 through its open end. In the

present instance, a material which is readily soluble in water, such as a soluble salt (sodium chlorid, for example), may be employed. The bore of the bolt, in the construction shown in Fig. 1, may be completely 60 filled with such material except only a sufficient portion of its inner end to accommodate a closing device. In the construction shown in Fig. 1, the wall of the inner end portion of the bore may be adapted for the 65 reception of a plug which, in the present instance, may be a brass screw 14. Instead of forming a bolt with a bore open at the inner end and extending partially through the bolt, as above explained, a bolt 15 of the 70 rigid type shown in Fig. 2 may be formed with a bore 16 extending from end to end thereof and containing the soluble material 13, both ends of said bore being temporarily closed by means of suitable plugs 16a,—or 75 the bolt may be made with a bore 17 extending from end to end and filled with the soluble material, and the respective ends of the bore left open as shown in Fig. 3.

To test the bolt, the attendant will examine 80 the contents of the bore. Such examination may be accomplished with the use of a wire inserted into said bore if a salt is employed. If he finds the powdered dissolvable material to be intact, he will 85 know that the bolt is good, and he may then replace the plug or screw. In the event that the bolt has become broken so as to admit water into its bore, such water will have dissolved the salt or similar material 90 and upon examination, the attendant will find that the bore is more or less clear of solid matter and this fact will indicate to him that the bolt is broken.

I do not wish to confine myself to the 95 specific construction of stay bolt structure herein shown and described, but my improvements may be made applicable to any such structure in which the bolt may be provided with a bore in which material 100 sensitive to the action of water may be contained.

Having fully described my invention what I claim as new and desire to secure by Letters-Patent, is:—

1. A stay bolt having an opening and material contained in said opening which is sensitive to the action of water to denote the condition of the bolt, said opening being readily accessible from an end of the bolt 110

- to permit examination of the contents of said opening, whereby the condition of the bolt may be determined.
2. A bolt having a hole therein accessible from an end of the bolt, and readily soluble material contained within said hole.
3. In a stay bolt structure, a stay bolt having a bore containing material readily soluble in water and removable means normally sealing said bore.
4. In a stay bolt structure, a stay bolt having a bore permanently closed at one end and having a removable closure at the other end, said bore containing material readily soluble in water.
5. In a stay bolt structure, a headed stay bolt having a bore open at its inner end and extending approximately to the head at the opposite end of the bolt, said bore containing material readily soluble in water, and a plug inserted into the inner open end of said bore.

In testimony whereof, I have signed this specification in the presence of two subscribing witnesses.

JOHN ROGERS FLANNERY.
